[57] **ABSTRACT**

A hand-powered machine is provided for producing business forms retained in the machine with concurrent issuance of receipts to a customer, the machine being particularly adapted for the production of sweepstakes forms. Electrical control is provided by which the number of forms to be issued in a complete transaction may be determined by dialing.

MACHINE FOR PRODUCING BUSINESS FORMS

BRIEF SUMMARY OF THE INVENTION

In connection with the issuance of sweepstake tickets it is desirable to retain the tickets of significance within an issuing machine in the form of a continuous strip thereof from which they may be individually severed under supervised circumstances for ultimate location in a receptacle from which drawings are made. The tickets thus provided are the sole tickets of value, but it is desirable to issue to a patron receipts for the psychological effect of showing to him that the machine has operated through a proper cycle, even though the receipts have no value in themselves. The patron's operation is one of writing his or another's name and address on the receipt with reproduction thereof on a carbon copy constituting one of the tickets retained in the machine. The general aspects of what is involved in such a transaction are described in the U.S. Pat. to Joseph C. Wagner, No. 3,273,914, dated Sept. 20, 1966.

The present invention provides a reliable but inexpensive machine performing the end functions of the machine of said patent. A program of producing sweepstakes tickets involves the use of many machines at a very large number of localities so that low cost is a quite important consideration. In accordance with the invention the machine is hand powered by necessary manipulations of a patron; and to reduce to a minimum the attention of an attendant provision is made for control of the issuance of a predetermined number of tickets in a single complete transaction, the determination of the number being effected by a single dialing operation following the payment of the correct amount by the patron.

BRIEF DESCRIPTION OF THE DRAWINGS

FIG. 1 is a top plan view of operating elements of a preferred type of machine, a top cover plate being omitted along with elements of a conventional tamper-proof housing which may be conventional;

FIG. 2 is a vertical section on a transverse plane indicated at 2-2 in FIG. 1 but showing additionally the cover plate and in fragmentary form walls of the housing;

FIG. 3 is a vertical section taken on the plane indicated at 3-3 in FIG. 1;

FIG. 4 is a fragmentary elevation, partly in section, to show more clearly certain of the elements hidden in the other views;

FIG. 5 is a vertical section taken on the plane indicated at 5-5 in FIG. 1;

FIG. 6 is a vertical section taken on the plane indicated at 6-6 in FIG. 1; and

FIG. 7 is a schematic diagram of the electrical elements involved.

DETAILED DESCRIPTION

Consideration will be first given to the mechanical construction involved.

A housing having walls typified at 2 is surmounted by a cover plate 4 having an opening 6 of sufficient dimensions to present a write-in area through which, as will be later explained, a patron may inscribe his name and address. The front of the machine is toward the reader

as FIG. 2 is viewed and at the right of FIG. 1 and the several vertical sections, the front being defined as the location adjacent to the patron. Without describing its very conventional details, the housing has its parts connected to prevent access from the exterior except through a locked door (not shown) through which authorized loading and unloading of the machine may take place.

When the machine is in idle, rest position, the opening 6 is covered by a slide 8 mounted at the lower face of the cover plate 4 and provided with an externally accessible knob 10 by which it may be moved backwardly and forwardly by a patron, the opening 6 being uncovered when the knob is moved toward the left as viewed in FIG. 2. Below the cover plate and slide there is located a table 12 which, as most clearly shown in FIG. 6, has at its rearmost portion a curved guide 14 and at its forward edge an upwardly curved guide portion 16 for presenting receipts to be removed. Fed across this table are portions of a two-ply strip of paper, the lower ply A of which is to be retained in the machine while the upper ply B, having a carbon backing is projected outwardly so that portions thereof may be torn off by a patron. The lower ply A after passing the write-in area moves downwardly through a slot 18 and thence through a guide 20 to pass downwardly into the reception portion of the housing wherein it is retained in a fanfolded form, the two-ply supply being originally in the same folded condition for upward and then horizontal movement over the table 12. A transverse bar having a sharp lower edge is provided at 22 so that the issued receipts may be torn off by a patron. Hinged and spring urged downwardly are guide members 24. Through slots in guide members 24 and in the table there advance feed pins 28 carried by chains 26 trained over sprockets 27 to feed the two-ply paper perforated at its edges to receive the pins to be fed thereby.

A rack 30 is secured to the slide for back and forth movement therewith. This rack is supported at its rear end by an idler pinion 31 and meshes with a pinion 32 to which it imparts movements, the pinion 32 meshing in turn with a gear 34 for imparting back and forth movements to a shaft 36.

The shaft 36 has secured thereto a driving clutch element 38 consisting of a hub provided with a notch 40. Journaled on the shaft 36 is a disc 42 which along with a U-shaped lever 44, pivoted to it at 46, constitutes a driven clutch element. The lever 44 has a projection 48 which enters the notch 40 when clutch engagement occurs, a spring 50 urging the lever in a counterclockwise direction relative to the disc 42.

The turned end 52 of a lever 56 is arranged to engage a shoulder 54 of the disc 42, and when the machine is in rest position it engages the left-hand portion of the lever 44. The lever 56 is mounted on a fixed pivot 58 and has a horizontal arm 60 which is engageable and held downwardly by a block 62 secured to the rear end portion of the rack 30, the arm of the lever being also provided with a cam portion 64 capable of effecting rocking of the lever by the block 62. The lever 56 is arranged to be rocked counterclockwise by a light spring 66 to position it for engagement with the shoulder 54, though this spring is insufficient to overcome the force of the strong spring 50 during the operation as hereafter described.

The plunger of a solenoid 68 is link-connected to the lower end of a lever 70 and is pivoted at 72 in such fashion that a rearward extension 74 engages as a detent the teeth of the rack 30 under the action of a spring 76 to prevent rearward movement of the rack when the machine is in rest position (FIG. 5).

The disc 42 has secured to it a gear 78 which meshes with a pinion 80 secured to a transverse shaft 82 (on which the pinion 32 is journaled) extending across the machine and having secured thereto the sprockets driving the feed chains 26.

A detent 84, pivoted at 86 and held downwardly by a spring 88 prevents clockwise rotation of the gear 78 (FIG. 4).

A cam projection 90 is arranged to engage the roller 92 of a switch 94 when the machine is in stationary condition.

The machine is manually operated by a patron, though desirably electrically controlled by an attendant. The electrical control may be of various types, of which one will be described hereafter for the production of a number of forms for a single patron. But it will be convenient to describe first an operation as mechanically effected by a patron.

The electrical control, whatever its detail nature may be, produces energization of the solenoid 68 to rock clockwise, as viewed in FIGS. 3 and 5, the lever 70 to pull its arm 74 downwardly out of engagement with the rack 30 which it has held previously against movement. The solenoid remains energized for an extended period during the operation, as will appear hereafter. The freeing of the rack enables the patron to push the knob 10 rearwardly and so move the slide to open up the aperture above the write-in area. As the rack moves rearwardly it effects clockwise rotation of the shaft 36. The initial movement of this shaft carries the notch 40 clockwise beyond the position of the tooth 48 of the lever 44, and only after this does the block 62 clear the upper end of the cam slope 64 of the lever 56 so that this releases the left-hand end of the lever 44 so that it may be rocked counterclockwise by the spring 50. This counterclockwise movement causes the tooth 48 to drop on the cylindrical surface of the driving clutch element 38 so that the clutch is not engaged at this time, and to insure that the driven element of the clutch is not rotated, the detent 84 (FIG. 4) prevents its clockwise rotation. The chains carrying the pins for driving the two-ply paper strip remain stationary. The operator, therefore, may fully open the slide to expose the upper ply of paper.

The patron may then write on the top ply his name and address in accordance with instructions which may be printed on that ply or otherwise presented in association with the machine, the name and address being transmitted to the lower ply by reason of the carbon backing of the upper ply.

In order to secure a receipt, the patron must then move the knob 10 forwardly and thus close the slide.

Before the end of the slide-opening operation, the lever 56 will have been rocked fully clockwise and as the notch 40 reaches alignment with the tooth 48, the latter will drop into the notch, the engagement resulting in limitation of the clockwise rotation of the shaft 36, this also involving the limitation on the movement of the slide. The end 52 of the lever 56 will move out sufficiently to clear the shoulder 54 of the driven clutch

disc. As forward movement proceeds, the rack 30 will effect counterclockwise rotation of the shaft 36, and the clutch being now engaged will effect driving of the gear 78 counterclockwise and driving of the pinion 86 and the sprocket shaft 82. These movements are permitted by the detent 84. The driving of the chains carrying the feed pins by the sprockets effects forward movement of the two-ply strip to advance the lower ply to the interior receptacle of the machine and present the outer ply to the patron. The receipt end rises over the guide surface 16 and as the knob 10 reaches the end of its forward movement the receipt is fully projected and may be torn off.

During the forward movement of the rack 30 the solenoid 68 is released so that the upper end of the lever 70 reengages the rack to prevent its reversal. As the rack 30 approaches the end of its forward movement, the block 62 will engage the cam end 64 of the lever 56 to rock it counterclockwise to place its end 52 in the path of the shoulder 54 and also to engage the left-hand end of the lever 44 to withdraw the tooth 48 from the slot 40 to disengage the clutch against the action of spring 50. The parts are thus brought to rest in their original position but with a new area of the strip beneath the write-in opening but now covered by the slide.

The electrical control may take a wide variety of forms, and FIG. 7 is merely exemplary of a preferred type of operation in which an attendant manipulates a dial of telephone type to choose the number of forms which a patron may produce in a single overall operation and for which he has paid. Each machine contains a conventional stepping relay 96 of which only so much is indicated as pertains to the special operations. To the extent indicated the relay comprises an adding solenoid 98 and a subtracting solenoid 100 arranged to provide in usual fashion the forward reverse movement of a contact 102 arranged to engage fixed contacts 104 in suitable number. A dial 106 is connected to a source of current supply 108 and the solenoids 98 and 100 are returned to ground (not shown).

One dial 106 may be provided for a group of machines so as to set them up individually through selection switches. It will be understood that each of the stepping relays may have the usual additional contact connections such as, for example, to provide for correction of an error by returning the contact 102 to its zero rest condition.

The solenoids 98 and 100 may be assumed to be of the usual type in which energization contacts a pawl so that when the solenoid is de-energized, the spring action moves the contact 102 either forwardly or rearwardly.

The final contacts 104, except the one in the rest position, are connected together and to a line 10 running to a pair of switches 112 and 114 within the switch heretofore designated 94. When the switch 94 is engaged by the cam 90 the switch contacts 112 are open, and the switch contacts 114 are closed. The contacts 114 provide a connection to the solenoid 68 which, when energized, withdraws its detent releasing the rack and the slide.

The contacts 112 when closed provide energization of the subtraction solenoid 100.

The withdrawal operation involves the following: If the attendant is paid for a certain number of forms to be issued, he may dial that number to advance the movable contact 102 to the corresponding fixed contact. Since the contacts 114 are closed, the solenoid 68 is energized releasing the slide for backward movement by the patron as described. It will be noted that the cam 40 does not move when the slide is moved rearwardly, and accordingly the solenoid remains energized to permit a complete rearward movement of the slide.

The patron may now enter his name and address and move the slide forwardly to issue the receipt and advance the lower strip into its storage. As this forward movement of the slide takes place, the cam 90 releases the switch 94 and therefore the contacts 112 are closed and the contacts 114 are opened. When the latter occurs, the solenoid 68 is de-energized, but the detent will not interfere with complete forward movement of the slide, though after a partial forward movement it cannot be moved forwardly.

The closure of the contacts 112 effects energizing of the subtract solenoid 100 arming its pawl for an ultimate backward movement of the contact 102. When the cam 90 reaches its final position, the switch 94 is engaged and the contacts 112 and 114 are restored to their initial positions. The opening of contacts 112 will produce a backward step of the contact 102. If after this step the contact again engages one of the fixed contacts 104 other than the one in the rest position, the solenoid 68 will be again immediately energized and the machine is in a condition in which the slide is released for the making of another entry on the strip, then the cycle may be completed as before.

However, if the contact 102 moves to its rest position, the solenoid 68 will not be energized even though the contacts 114 close, and therefore the slide cannot be again re-opened. It will be noted that a second re-opening cannot be effected unless it is preceded by a full closure. The machine finally achieves a condition for another manipulation of the dial 106 by the attendant.

I claim:

- 10 1. A machine for producing business forms comprising an enclosure, a table therein, means for feeding a multi-ply strip across said table to present an upper ply to a patron and deliver a duplicate to an inaccessible location within the enclosure, said enclosure having an opening above the table to permit the patron to make entries on the upper ply, a manually movable cover normally closing said opening, means locking the cover in closed position, means for unlocking the cover for manual opening by a patron, means connecting the cover to said feeding means so that the power applied in manual closure of the cover by a patron effects the aforementioned operation of the feeding means, and means preventing reopening movement of the cover after initial movement towards closed position until it is fully closed and then unlocked.
- 15 2. A machine according to claim 1 having control means including manually selectable means for entering an initial selection of a number of business forms to be produced from a group of possible selections, and
- 20 30 means responsive to said manually selectable means for permitting only the number of operations of the machine sufficient to produce the selected number of forms, following such initial selection.
